UNITED STATES PATENT OFFICE.

ELIZA C. KINDRICK, OF NASHVILLE, TENNESSEE.

REFRIGERATOR.

No. 817,782.

Specification of Letters Patent.

Patented April 17, 1906.

Application filed August 1, 1903. Serial No. 167,916.

To all whom it may concern:

Be it known that I, ELIZA C. KINDRICK, a citizen of the United States, residing at Nashville, in the county of Davidson and State 5 of Tennessee, have invented a new and useful Refrigerator, of which the following is a specification:

My invention is an improvement in refrigerators; and the object of the invention is 10 to provide a device of this kind which can be readily cleaned and will be at all times properly ventilated.

Another object of my invention is to provide a convenient arrangement of the various compartments with reference to a central ice-compartment.

With these objects in view my invention consists of the novel features of construction and combination of parts hereinafter described, particularly pointed out in the claims, and shown in the accompanying drawings, in which—

Figure 1 is a perspective view of my refrigerator. Fig. 2 is a vertical section 25 through the refrigerator; and Fig. 3 is a section on the line 3 3 of Fig. 2, the filter and a portion of the ventilating-pipe being in elevation.

In the drawings, A represents the exterior 30 casing of the refrigerator, which may be of polished oak or any suitable wood. The interior lining B is of zinc or porcelain and is secured to an inner casing A'. A suitable packing material A² is arranged between the 35 casings A and A'. Supported by suitable cleats and cross-bars is a horizontal partition C, arranged just above the bottom of the inner casing. Resting on this partition and transverse to it are the vertical partitions C', 40 and a horizontal partition C², arranged between the partitions C', about midway their height, completes the permanent divisional walls. This arrangement gives a milk-compartment taking up the lower portion of the 45 refrigerator, an ice-compartment (shown at C³) arranged in the central portion of the refrigerator, a water-compartment immediately above the ice-compartment, and meat and vegetable compartments on each side of 50 the water and ice compartments. Cleats C⁴ are arranged in these side compartments, and sliding slotted partitions C⁵ rest on the cleats.

An opening is formed in the top of the refrigerator, and a porous filter D is arranged in

the water-compartment and extends upward through the top of the refrigerator. A discharge-faucet E is arranged in the front of the water-compartment, by means of which the water may be drawn off for use. Suitable doors of the usual type are adapted to close the front of the compartments, excepting the water-compartment, which is filled through the filter and cleaned by removal of the latter. Small perforations F are formed in the upper portion of each door 60 excepting that of the ice-compartment, and these perforations may be closed by small plugs F'. The doors all swing in a horizontal plane with the exception of the door to the milk-compartment, which is hinged along 65 its lower edge and swings vertically. Perforations G are formed in the partition C, adjacent the rear wall, opening upwardly into the ice-compartment and downwardly into the milk-compartment, permitting the cold 70 air to settle in this lower compartment and also allowing drainage for water from the melting of the ice. A short drain-pipe H opens downwardly through the floor of the milk-compartment. A ventilating-pipe I extends up the rear of the refrigerator and at 75 its lower end communicates with the upper portion of the milk-compartment. Branch pipes J lead from the upper portions of the side compartments through the rear wall and 80 communicate with the vertical pipe I, which latter pipe opens upwardly above the top 85 of the refrigerator.

It will be obvious that by removing the plug F' a thorough ventilation of the milk 90 and vegetable compartments will be had, preventing the accumulation of foul air therein and the consequent tainting of the milk, vegetables, and meats. It will be further noted that no long drain-pipes are used, 95 as such pipes would be difficult to keep clean. Additional compartments may be formed by inserting extra divisional walls without departing from the construction here outlined, and where pure water is obtainable the filter 100 may be omitted and the opening in the top closed by a suitable cover. The side compartments provide separate chambers in which to place meats and vegetables.

Having thus fully described my invention, 105 what I claim as new, and desire to secure by Letters Patent, is—

A refrigerator comprising a plurality of

compartments having doors in the front thereto and adapted to contain articles of food, a ventilating-pipe arranged vertically at the rear of said refrigerator and having communication with the lower portion of said refrigerator, the doors of said compartments having each a perforation adjacent their upper edge, and means for closing said perforations.
